REINFORCED RESILIENT SHOE HEEL

Frank Cleve, Jr., Kansas City, Mo.

Application May 21, 1945, Serial No. 594,915

6 Claims.

(Cl. 36—75)

This invention relates to footwear in general and particularly to that portion of a shoe designated "heel," and the primary aim is to provide a resilient, reinforced shoe heel having inserts of relatively rigid substance.

One of the important aims of this invention is to provide a reinforced, resilient shoe heel, the reinforcement whereof is specially formed to support the heel at particular areas, prevent excessive wear at such areas, and yet allow the heel to cushion the foot of the wearer the same as though the reinforcement were not present.

A further aim of the invention is the provision of a specially designed reinforcement for resilient shoe heels, which reinforcement is originally in the nature of an article of manufacture, the contour and character whereof is such as to accomplish the broad object of the invention when the same is in the operative position.

A large number of important objects will appear during the course of the following specification, referring to the accompanying drawing wherein:

Fig. 1 is an inverted plan view of a portion of a shoe, having a reinforced, resilient heel thereon, made in accordance with the present invention.

Fig. 2 is an inverted bottom perspective view of the insert entirely removed from association with the resilient body of the heel.

Fig. 3 is a top plan view of the insert.

Fig. 4 is a cross sectional view taken on line IV—IV of Fig. 3; and

Fig. 5 is an enlarged fragmentary detailed sectional view taken on line V—V of Fig. 1.

I am aware that metallic inserts have been used in the construction of rubber heels and that such inserts have failed in their purpose. It is further known that metallic inserts have been formed in various ways in an effort to overcome excessive wear of the heel body without destroying the cushioning effect of the resilient heel.

It is apparent that the reason reinforced resilient shoe heels are not now generally accepted by the public, is that they fail to dissipate the shock and do not remain securely anchored in place.

The heel assembly made pursuant to my invention, overcomes these objections and may be worn without the inconvenience that has attended reinforced heels heretofore sold to the trade.

One form of the invention has been chosen for illustration and the reinforced heel is shown in the accompanying drawing attached to the shoe sole 10 by nails 12 that enter transverse openings

14 molded in the body 16 wherein insert 18 is embedded.

Body 16 is made of resilient or elastic substance such as rubber, and the insert 18 is formed of metal to present an appearance clearly shown in Figs. 2, 3 and 4.

Two inserts 18 should be employed in body 16 and their location is as illustrated in Fig. 1.

The insert per se is in the nature of a cup-shaped body having a perforated bottom wall 20, the perforation 22 whereof receives nail 12 when the heel assembly is to be mounted. The annular side wall of the substantially cup-shaped body of insert 18, is divided into a number of segments 24, each having the free edge 26 thereof exposed at the outer or bottom surface of resilient body 16, as plainly seen in Fig. 1. These segments 24 are spaced apart and reduced in cross sectional area at their zones of juncture with bottom wall 20. This reduced portion of each segment 24 is in the nature of a neck 28, the resiliency whereof is increased over that of the remaining part of the body to allow a "spring" when an impact is imparted to edges 26. Each segment 24 has a shoulder 30 on each edge thereof to underlie a substantial amount of resilient material forming body 16 when the insert 18 is embedded as shown in Fig. 5, thus, any impact imparted to edges 26 is partially dissipated by the resiliency of neck 30 and by the cushioning effect of the material from which body 16 is made and that lies between shoulders 30 and the bottom of shoe sole 10.

In addition to these two features of insert 18, which contribute to the desirability of this form of insert, the said insert is designed to cause body 16 to absorb a part of the shock by having the zone of juncture, or neck 28, arched as shown in Figs. 4 and 5. The convex arched surface 32 of each neck 28 distributes the force due to striking edges 26 through a relatively large mass of body 16 and in the direction of the arrows shown in Fig. 5. Thus, the insert 18 cooperates with resilient body 16 in cushioning the steps of the wearer as it prevents undue grinding away of the material from which body 16 is made, at the points where the inserts are placed.

The insert is positioned in body 16 when the latter is molded and serves to reinforce the heel at a point where most needed.

Having thus described the invention, what is claimed as new and desired to be secured by Letters Patent is:

1. A reinforced resilient shoe heel of the character described, comprising a body of elastic substance; and an insert embedded in the body with

faces thereof exposed at the wearing surface of the body, said insert being an inverted cup-shaped element having a perforated bottom for the reception of a nail and a segmental side wall, the segments of the side wall each having lateral shoulders thereon to increase the shock dissipating surface of the insert.

2. A reinforced resilient shoe heel of the character described comprising a body of elastic substance; and an insert embedded in the body with faces thereof exposed at the wearing surface of the body, said insert being an inverted cup-shaped element having a perforated bottom for the reception of a nail and a segmental side wall, the segments of the side wall each having lateral shoulders thereon to increase the shock dissipating surface of the insert, said shoulders being at the zone of juncture between the segments and the bottom of the insert.

3. A reinforced resilient shoe heel of the character described comprising a body of elastic substance; and an insert embedded in the body with faces thereof exposed at the wearing surface of the body, said insert being an inverted cup-shaped element having a perforated bottom for the reception of a nail and a segmental side wall, the segments each having a reduced portion at their zones of juncture with the bottom to increase the resiliency of the insert at said zones.

4. A reinforced resilient shoe heel of the character described comprising a body of elastic sub-

stance; and an insert embedded in the body with faces thereof exposed at the wearing surface of the body, said insert being an inverted cup-shaped element having a perforated bottom for the reception of a nail and a segmental side wall, the segments each having a convex outer surface at the zone of juncture with the bottom to spread the shock imparted to the segments.

5. A reinforced resilient shoe heel of the character described comprising a body of elastic substance; and an insert embedded in the body with faces thereof exposed at the wearing surface of the body, said insert being an inverted cup-shaped element having a perforated bottom for the reception of a nail and a segmental side wall, the segments each having a reduced portion at their zones of juncture with the bottom to increase the resiliency of the insert at said zones, the segments each having a convex outer surface at the zone of juncture with the bottom to spread the shock imparted to the segments.

6. As a new article of manufacture, an insert for resilient heels comprising a cup-shaped body of relatively hard substance having a perforated bottom wall; an annular side wall divided into a plurality of segments each reduced in cross sectional area at the zone of juncture with the bottom wall and arched at said zone to present a convex outer surface.
